Primary Examiner—James M. Gandy**Attorney, Agent, or Firm—Edgar A. Zarins; Malcolm L. Sutherland****[57] CLAIM**

The ornamental design for a vehicle top, as shown and described.

DESCRIPTION

FIG. 1 is a perspective view of a vehicle top showing my new design in position of use on an automobile which is shown in broken lines for illustrative purposes only and forms no part of the claimed design;

FIG. 2 is an enlarged top plan view thereof;

FIG. 3 is an enlarged right side view thereof; the opposite side being a mirror image of the side shown;

FIG. 4 is an enlarged front elevation view thereof; and.

FIG. 5 is a rear elevation view thereof.
